UNITED STATES PATENT OFFICE.

WILLIAM GRAY DUNHAM, OF BRANTFORD, ONTARIO, CANADA.

JOURNAL-BOX.

968,033.

Specification of Letters Patent. Patented Aug. 23, 1910.

Application filed August 29, 1908. Serial No. 450,872.

To all whom it may concern:

Be it known that I, WILLIAM G. DUNHAM, a citizen of the United States, residing at Brantford, in the county of Brant, Province of Ontario, Canada, have invented certain new and useful Improvements in Journal-Boxes, of which the following is a specification.

My invention relates to journal boxes for 10 railway trucks.

The object of my invention, is to provide an improved form of lid or cover which will render the box easily accessible for inspection or repairs.

15 A further object, is to provide a lid which will allow the use of the box with a low down body or frame.

A further object, is to provide a journal box having a lid which when open, may be 20 utilized as a shelf during the operation of renewing the journal bearing key, brass and packing.

A further object, is to provide a journal box lid, which will be as far as possible, dust 25 proof and oil tight, and of simple and economical construction.

30 A further object, is to dispense with the use of all pins, rivets, or bolts generally employed for securing the lid to the journal box.

A further object, is to provide a journal box having means for attaching the lid thereto, which is all inclosed within the walls of the box, thus making it impossible for any 35 of the parts to become lost.

A further object is to provide a lid which cannot be opened except by the use of a proper tool.

40 My invention consists generally in a journal box having its lid hinged at its lower end, on the box.

Further, the invention consists in a spring mechanism normally securely locking the lid in its raised or closed position, but adapted 45 to hold the lid when it is swung down to a horizontal or open position.

Further the invention consists in improved means for pivoting the lid in the box whereby it is held securely in place, thus reducing 50 liability of heated journals due to loss of journal box lids, suitable means being provided whereby the journal box lid may be removed when necessary.

Further the invention consists in seating 55 the lid in the wall of the box, whereby it will

be rendered practically dust proof, and oil tight.

Further the invention consists of various constructions and combinations, all as hereinafter described, and particularly pointed 60 out in the claims.

In the accompanying drawings forming part of this specification, Figure 1, is a front elevation of a journal box with a portion of its wall broken away, illustrating the 65 manner of mounting the lid therein. Fig. 2, is a sectional view of the box showing the lid in its closed position, Fig. 3, is a detail sectional view showing the lid open. Fig. 4, illustrates a portion of the wall of the box 70 with the lid removed therefrom. Figs. 5 and 6 and 7, are detailed views of the lid.

In the drawing, 2 represents the journal box and 3 the lid. Generally in boxes of this kind, the lid is hinged at the top and 75 is swung upward by the inspector to open the box and inspect the bearing. When the lid is hinged at the top of the box, it frequently cannot be swung high enough to permit convenient inspection of axle, brass 80 and packing as the lid will come in contact with the car body or its frame work.

The tendency in modern railway car construction, is to set the car body as low as practicable, and this construction, I have 85 made possible, by hinging my journal box lid at the bottom and allowing it to swing outwardly to a horizontal position where it will not only permit convenient access to and inspection of the box, but will serve as 90 a shelf on which articles removed from the box may be temporarily placed.

The journal box and the lid are of the same construction on both sides, and hence a 95 detailed description of one of the hinges will be sufficient, it being understood that both edges of the lid are supported in the same manner. The wall of the box has a recess 4 adapted to receive a pivot pin 5 which projects laterally from a flange 6 on the lid 100 3. This pivot pin fitting within the recess 4 forms a hinge for one side of the lid. A seat 7, is provided in the wall of the box, and a flange 8 incloses the seat and forms with the lid, a dust proof joint. A stop 9 is provided on the lid in a position to engage the edge 10 of the recess 4, and prevent vertical vibration of the lid. At the lower end of the lid, webs 11 are formed having projections 12 which overhang the wall 13 and 110

are recessed to receive the edge of said wall and form therewith, a close joint to retain the oil and prevent the entrance of dust and dirt into the box under the lower edge of 5 the lid. A bracket 14 forms a continuation of the flange 6 and has recesses 15 and 16 in its edge between which a curved cam track 17 is formed. The wall of the box on each side, is provided with a projection or 10 housing 18 in which is a sliding spring detent 19 adapted to receive one end of a coiled spring 20, that is seated at its upper end in a recess 21. An opening 22 leads through the wall of the box into the housing 18 and said opening communicates with a slot 23 in which a lug 24 formed on the detent 19 is slidable. This lug, is adapted to bear on the edge of the bracket 14 and ride thereon during the movement of the lid. 15

20 When the lid is closed, the lug will rest in the recess 16 at one side of the pivot of the lid, and the tension of the spring 20 will be sufficient to hold the lid in its closed position, and also to swing it shut when it 25 has lifted past a predetermined point. In the opening of the lid, the lug 24 slides on the edge of the bracket until it reaches the point indicated in Fig. 3, where it will fit within the recess 15 and having swung past 30 the center of the lid pivot, the tension of the spring will be exerted to hold the lid in its open position. The lower end of the lid, contacts with the wall of the box as indicated in Fig. 3, and forms a stop to limit 35 the downward movement of the lid. When the lid is closed, the bracket 14 swings down within a housing 25 which serves as a guard for the bracket and prevents the journal packing from working therein. I also prefer to provide a series of teeth 26 on the wall of the housing and also on two webs 26' which extend inwardly from the front wall of the box. These teeth engaging the 40 packing, prevent upward creeping of the same. The spring detent 19 has a socket 27 therein, into which a pin may be thrust when the detent is adjusted in the position shown in Fig. 4, for the purpose of relieving the lid of the pressure of the spring, and 45 allowing it to be easily removed from the box. To apply the lid to the journal box, place the spring detent in its socket and insert the spring, then raise the spring detent and lock it by means of the retaining 50 pin, insert the pivot pin in recess 4 leaving the lid in an open position, then remove the retaining pin, and the lug on the spring detent will be moved into contact with the lid bracket, and the lid be held thereby, 55 either in an open or closed position. When the lid is in an open position, it will be securely held and should the spring become weak in case of excessive heating of the journal box, the lid cannot become detached 60 and lost.

It will be noted that the lid and its connections are all cast in one piece, thereby saving considerable expense in the manufacture of the journal box and obviating entirely the danger of losing the parts and 70 making fewer joints than are usually found in boxes of this kind.

The lid of the box when closed, fits snugly within the flange 8 and it will be impossible for any mischievously inclined person to 75 open the lid and remove the packing or damage the box without the aid of some form of tool. To enable the inspector to open the lid, I provide a recess 28 in the cover 3, having a pin 29 extending across 80 it and cast in the lid that is adapted to be engaged by the inspector's tool for the purpose of pulling the lid to an open position. Pin 29 will be substantially flush with the outer face of the lid, and will have no projecting parts which might strike some other object and cause damage to the box. 85

I claim as my invention:

1. A journal box having housings in its side walls forming spring pockets, and slots 90 in said walls communicating with said pockets, said side walls having recesses and entrance openings thereto at right angles substantially to said recesses, springs within said pockets, sliding detents therefor having lugs projecting through said slots, and a lid having pins fitting within said recesses and brackets adapted to engage said lugs, substantially as described. 95

2. A journal box having housings formed integrally with its side walls, and slots in 100 said side walls leading into said housings, springs provided in said housings and detents therefor having lugs projecting through said slots, said walls having recesses therein, a lid having pivot pins adapted to enter said recesses, and said lid having means adapted to engage said lugs and put 105 said springs under compression, when the lid is opened, said slots and said pivot pins 110 being located within the box and concealed when the lid is closed, substantially as described. 115

3. In a journal box, a lid having webs or flanges thereon, and brackets projecting 115 from said flanges, and having recesses therein, and cam surfaces between said recesses, studs or pivot pins formed on said brackets, and said lid having stops near said studs and said lid, flanges, brackets, studs 120 and stops being all cast in one piece.

4. A journal box, having pockets formed in its side walls, and springs fitting within 125 said pockets, and detents adapted to engage said springs, and having lugs projecting through the walls of said pockets, and a lid hinged at its lower end on said box and having brackets adapted to engage said lugs, substantially as described. 130

5. A journal box for railway cars having 130

pockets in its side walls and springs fitting therein, detents arranged to engage said springs and having laterally projecting lugs, a lid hinged to the lower wall of said box and having brackets to engage said lugs, and the hinging of said lid and said detents and brackets being entirely concealed when the lid is closed.

5 6. A journal box for railway cars having a lid hinged thereon at its lower end and adapted to swing upwardly to a closed position, said box having recesses in its side walls and sliding detents therein, and said lid having pins projecting therefrom and 10 15 yieldingly held by said detents, substantially as described.

7. The combination, with a journal box, of sliding detents mounted in recesses provided in the side walls of said box and extending vertically therein, means for yieldingly resisting the upward movement of 20 said detents, and a lid hinged at its lower end on said box and having means engaging said detents, and said detents resisting the downward movement of said lid and 25 normally tending to hold it in its closed position until it is swung down past a predetermined point.

8. The combination, with a journal box 30 having recesses in its side walls, of a lid having studs to enter said recesses, and form pivots for the lid, and stops provided on said lid, and adapted to engage the edges of said recesses and prevent vibration of 35 said lid.

9. The combination, with a journal box, of a lid having brackets formed thereon, and studs projecting laterally therefrom, said brackets having recesses formed there- 40 in with cam surfaces between them, said box having spring pockets and springs therein in its side walls and sliding detents for said springs, said detents having lugs projecting into said box through slots in the 45 walls thereof, and engaging said brackets with a yielding pressure, said lugs entering the recesses in said brackets on one side of said cam surfaces when the lid is closed, and holding it in its closed position, and said 50 lugs sliding on said cam surfaces and entering said other recesses in said brackets when said lid is swung to a horizontal position.

10. The combination, with a journal box

having spring pockets formed thereon, and slots communicating with said pockets, of a lid hinged at its lower end on said box and having inwardly projecting brackets, springs within said pockets, sliding detents therefor, having lugs projecting through said slots in the path of said brackets, and said 55 detents having sockets to receive pins whereby said seats may be temporarily locked in an inoperative position and said box having recesses in its side walls with openings leading thereto and adapted to receive pivot 60 pins projecting from said brackets, said lid being readily removable from said box when necessary.

11. The combination, with a journal box having recesses in its inner side walls opening into the space within said box, of a lid having laterally extending pivot pins near its lower edge and adapted to enter said recesses, means mounted in the side walls of 70 said box and concealed when the lid is closed 75 and yieldingly resisting the movement of said lid to an open position.

12. The combination, with a journal box, of a lid hinged in its lower end thereon, means for exerting pressure on said lid to 80 hold it in an open position when swung past a predetermined point, said means being mounted in the side walls of said box and invisible when the lid is closed and having a part projecting into the path of said lid 85 and yieldingly resisting outward movement thereof.

13. The combination, with a journal box, of a lid hinged at its lower end thereon, the pivots of said lid being invisible when the lid is closed, and means adapted to hold 90 said lid in an open position when swung down past a predetermined point, said means fitting within pockets or recesses in the side walls of the box and including sliding detents and yielding backings therefor, 95 said detents having parts projecting into the path of said lid.

In witness whereof, I have hereunto set my hand this twenty-second day of August 100 1908.

WILLIAM GRAY DUNHAM.
